UNITED STATES PATENT OFFICE

JULIUS VOSS, OF WIESBADEN-BIEBRICH, GERMANY, ASSIGNOR TO KALLE & CO. AKTIENGESELLSCHAFT, OF WIESBADEN-BIEBRICH, GERMANY

PROCESS AND DEVICE FOR DRYING TUBULAR BODIES

Application filed March 28, 1930, Serial No. 350,664, and in Germany September 15, 1927.

The present invention relates to process and device for drying tubular bodies.

Various processes are known for drying tubular bodies, for instance sausage casings, i. e. skins, guts, tubular bodies made of cellulose or the like, by fastening the ends of measured pieces of the tubular bodies of a relatively short length, mostly one of a few meters, to the front-walls of a drying chamber, while hermetically closing one end and blowing air into the other end so that the tubular body is inflated, and then drying it by the action of air or hot gases. This process involves much manual labor and there are obtained dry tubular bodies of at best only a few meters length. Said process is, therefore, not suitable if it is intended to dry tubular bodies having a length of several hundreds of meters, such as they are for instance obtained by spinning viscose by means of an annular nozzle.

I have found that tubular bodies of considerably greater length can be dried by passing them through a drying chamber in an inflated state instead of treating the wet tubular body in a drying chamber while at rest by inflating it, so that it enters one end of the drying chamber, while being wet and leaves the drying chamber at the other end, in a dry state.

It is necessary to conduct the air which is needed for inflating the wet tubular body, through the already dried tubular body so that also the latter is always inflated.

The following examples serve to illustrate the invention, but they are not intended to limit it thereto:

Fig. 1 is a schematic drawing of a device wherein the material passes through the drying chamber once.

Fig. 2 is a modification of Fig. 1 wherein the material passes through the drying chamber a number of times.

Fig. 3 is a cross-section of a modified device wherein the tubular body to be dried passes through the drying chamber in a spiral a number of times, and Fig. 4 is a horizontal plan of the device shown in Fig. 3.

1. As may be seen from Fig. 1, the tubular body which is wound as a flat bend-like form

upon a spool *a* is conducted by the squeezing rollers *b*₁ and *b*₂ into the drawing chamber *c* and fastened to the nozzle *e*₁ of the winding drum *d*₁. Air is then blown through the nozzle *e*₁ into the tubular body, whereby it is inflated as far as the squeezing rollers *b*₁ and *b*₂. While blowing warm air through the tubes *f*₁ and *f*₂ into the drying chamber, the tubular body is slowly conducted in the direction of the arrow through the drying chamber at such a velocity that it leaves the drying chamber at *g* in a dry state. The tubular body is then wound up in a spiral upon the winding drum *d*₁ which is also turned in the direction of the arrow. When the tubular body has been completely wound on the drum *d*₁, the tubular body is cut off and the tubular body emanating from the drying chamber is fastened to the nozzle *e*₂ of the second drum *d*₂, while blowing air through the nozzle *e*₂ into the tubular body; the further operations are carried out as above described.

2. A modification of the above described process by which it is possible considerably to increase the drying speed, is illustrated by Fig. 2. According to this method the tubular body is passed in several windings through the drying chamber. The wet tubular body wound in a flat band-like form upon the spool *a* is conducted between the squeezing rollers *b*₁ and *b*₂ into the drying chamber *c*, it then leaves the drying chamber and after having been wound round the drum *d*, it reenters the drying chamber. The tubular body is then carried around the drums *e* and *f* in several windings through the drying chamber and finally fastened to the nozzle *h* on the drum *g*₁. During the drying process there is blown air through the nozzle *h* into the tubular body travelling around the drum *g*₁ in the direction of the arrow. The dried tubular body leaving the drying chamber is also wound up on the drum *g*₁ while being permanently inflated.

Around the rollers *a*₁ and *a*₂ of the drying device shown in Figs. 3 and 4 there is wound in a spiral an india-rubber hose, if possible in as many windings as the capacity of the drums will allow. (See Fig. 4.) To the one end of the india-rubber hose is fastened the

hand-like tubular cellulose body which comes from the roll *b* and has to be dried, while the other end is drawn over the nozzle *d* fastened firmly to a drum *t* so as to lie close on it. Then air is blown into the tubular body through the tube *r*, the nozzle *d* and the india-rubber hose and by turning the drum *t* and the rollers *a*₁ and *a*₂ the tubular body is wound in a spiral on the rollers *a*₁ and *a*₂, so that at first the india-rubber hose and then the tubular cellulose body *S* carried along are wound on the drum *t*. Hot air is simultaneously introduced into the drying chamber *c*. The velocity of revolutions of the rollers and the temperature of the air are regulated in such a manner that the tubular body leaves the apparatus in a dry state. It is then wound on the drum *t* while permanently inflating it until it completely covers the drum. The tubular body is then cut off before the drum *t* and drawn over the nozzle of the drum *t*₁. Through the tube *r*₁ air is reintroduced into the tubular body, which is then dried while permanently moving it, while the dried tubular body in an inflated state is wound on the drum *t*₁. The tubular body wound on drum *t* is then cut open at the nozzle *d*, the air is allowed to escape as much as possible and the tubular body is wound on the spool *p* which thus takes place smoothly and without there being any formation of folds.

It is advisable to mount the drums upon a slide in order to be able to move them to the side while the tubular body is wound up so that the tubular body travels on the roller always in the same direction and cannot turn round itself.

I claim:

1. The process of drying tubular bodies of great length which consists in continually passing the tubular body in an inflated state through a drying chamber in such a manner that it runs in a straight line inside the drying chamber.

2. The process of drying tubular bodies of great length which consists in passing the tubular body in an inflated state through a drying chamber in such a manner that it runs in a straight line inside the drying chamber, and winding the dried tubular body in an inflated state on a drum.

3. Device for drying tubular bodies, which comprises a drying chamber, two drums, one for winding off the tubular body, the other for winding it on, the latter being provided with a nozzle for the introduction of compressed air into the tubular body to be dried.

4. Device for drying tubular bodies which comprises a drying chamber, two drums, one for winding off the tubular body, the other for winding it on, the latter being provided with a nozzle for the introduction of compressed air into the tubular body to be dried and two rollers fitted outside the drying

chamber, serving as a guide for the tubular body.

5. Device for drying tubular bodies which comprises a drying chamber, a drum for winding off the tubular body, two squeezing rollers, a drum for winding on the tubular body, said drum being provided with a nozzle for the introduction of compressed air into the tubular body to be dried.

6. Device for drying tubular bodies which comprises a drying chamber, a drum for winding off the tubular body, two squeezing rollers, a drum for winding on the tubular body, provided with a nozzle for the introduction of compressed air into the tubular body to be dried and two rollers fitted outside the drying chamber and serving as a guide for the tubular body.

In testimony whereof, I affix my signature.
